ACCESSORY AUTOMOTIVE SEAT CUSHION

John E. Heckethorn, P.O. Box 117,
Dyersburg, Tenn. 38024

Filed Sept. 7, 1966, Ser. No. 3,755

Term of patent 14 years

(Cl. D15—8)

FIG. 1 is a perspective view of an accessory automotive seat cushion showing my new design;

FIG. 2 is a front elevational view thereof; and

FIG. 3 is a left side elevational view thereof.

The right side is similar in appearance to, but of opposite hand of the showing in FIG. 3. The rear of the back portion and the bottom of the seat portion are plain and unadorned.

I claim:

The ornamental design for an accessory automotive seat cushion, as shown and described.
